UNITED STATES PATENT OFFICE.

ALTON H. BOWMAN, OF ALLENTOWN, PENNSYLVANIA, AND HENRY D. DESHLER, OF BELVIDERE, NEW JERSEY.

VENDING-MACHINE.

1,250,785.

Specification of Letters Patent. Patented Dec. 18, 1917.

Application filed May 27, 1915. Serial No. 30,811.

To all whom it may concern:

Be it known that we, ALTON H. BOWMAN and HENRY D. DESHLER, citizens of the United States, residing, respectively, at Allentown and Belvidere, in the counties of Lehigh and Warren, States of Pennsylvania and New Jersey, have invented a new and useful Vending-Machine, of which the following is a specification.

10 This invention relates to vending machines, one of its objects being to provide a simple and compact machine having comparatively few parts so that it will not readily get out of order.

15 A further object is to provide a machine of this character having means whereby the package, while being ejected from the magazine, will operate to open a coin shutter so that the coin deposited in the machine will 20 be directed into a coin receptacle, while the package will be delivered into a tray or other receptacle provided therefor, the coin shutter being so mounted as not to interfere with the fall of the package into its 25 receiving tray.

Another object is to provide means whereby a coin will not only be returned to the customer should it be deposited in an empty machine, but it will also be returned to 30 the customer should it be inserted into the coin receiving slot after the plunger has been pushed inwardly out of its normal position, thus preventing the machine from becoming clogged, as has heretofore been the case 35 under like conditions.

40 A further object is to provide a machine of this character so constructed that should a slug be deposited in the coin slot, it will be retained in the machine without either clogging the machine or effecting the delivery of a package, such retention of the slug preventing its reuse by the depositor.

45 A further object is to provide means whereby a coin smaller than that designed for use in connection with the machine, will be returned to the customer if deposited in the coin slot.

50 A further object is to provide a novel form of casing especially useful in connection with a single magazine machine, this casing being in one piece and being held in position by a lock of novel form.

A further object is to provide improved means whereby the machine can be adjusted

for use in dispensing packages of different 55 thicknesses.

With the foregoing and other objects in view which will appear as the description proceeds, the invention resides in the combination and arrangement of parts and in 60 the details of construction hereinafter described and claimed, it being understood that changes in the precise embodiment of the invention herein disclosed can be made within the scope of what is claimed, without departing from the spirit of the invention.

In the accompanying drawings the preferred forms of the invention have been shown.

70 In said drawings:

Figure 1 is a perspective view of a complete machine utilizing a plurality of magazines.

Fig. 2 is an enlarged vertical section taken 75 from front to rear of the lower portion of the machine and through one of the magazines and the mechanism coöperating therewith.

Fig. 3 is a section on line A—B Fig. 2, 80 two of the magazines being removed and the parts thereunder being shown in section.

Fig. 4 is a section on line C—D Fig. 2, 85 two of the magazines and the coin shutters combined therewith being removed.

Fig. 5 is a vertical section through the lower portion of the machine, said section being taken on the line E—F Fig. 4, and showing the slug passage into the coin box.

Fig. 6 is a section through a portion of the mechanism and showing the relative positions of the parts during the ejection of a package by an inserted coin.

Fig. 7 is a front elevation of a modified 95 form of machine especially designed for use in narrow spaces such as found between the windows of street cars and the like.

Fig. 8 is an enlarged section on line G—H Fig. 7.

Fig. 9 is a section on line I—J Fig. 8.

Fig. 10 is a section on line K—L Fig. 8.

Fig. 11 is a section on line M—N Fig. 9.

Fig. 12 is a section on line O—P Fig. 10.

Fig. 13 is a section through a portion of 105 the top of the machine and showing the lock used for holding the casing in position.

Referring to the figures by characters of

reference 1 designates a housing the front of which is open as at 2 while the bottom thereof forms a tray 3 which may be provided with a retaining rib or projection 4 extending from one side to the other of the bottom, this tray being designed to receive delivered packages as well as returned coins. Studs 5 are extended inwardly from the sides of the housing or casing 1 and are designed to be detachably engaged by hooks 6 formed at the upper and lower ends of flanges 7 extending inwardly from the sides of a front plate 8 adapted to fit snugly between the sides of the housing or casing 1 and to be supported by the studs above the bottom of said casing or housing as shown. This front plate 8 is adapted to be held in position by a panel 9 having a groove 10 in its lower edge for the reception of the upper edge of the plate 8, said panel fitting snugly between the sides of the casing 1 and under the top of said casing and being fastened by any suitable form of lock, indicated generally at 11. Thus it will be seen that when panel 9 is in position the front plate 8 will be securely held in place and cannot be removed until panel 9 has been unfastened and removed. This panel 9 serves to conceal the magazines and their contents except where openings 12 are provided near the lower end of the panel 9 through which certain of the contents are visible.

Extending inwardly from the front plate 8 at the sides thereof and at points between the upper and lower edges of the plates are arms 13 which support a plate 14 constituting a slide the ends of which are seated in grooves 15. This slide is provided with a longitudinal series of slots 16 and 17 designed to receive coins and slugs respectively, one slot 17 being interposed between every two slots 16 and there being a number of slots 16 equal to the number of magazines used in the machine. In the form of machine illustrated in Figs. 1 to 6 inclusive four magazines are employed and, consequently, there are four slots numbered 16 and two slots numbered 17, each slot 17 being located between two slots 16. Depending from the slide 14 so as to lie flush with the front and back walls of the slots, are segmental tongues 18 substantially semi-circular and of a diameter somewhat less than that of the coin to be used in connection with the machine. Each pair of tongues 18 forms a coin receiving slot or pocket therebetween. There are no tongues depending from the walls of the slots 17, as will be seen by referring to Fig. 3.

Secured upon the back face of the front plate 8 is an inclined guide plate 19 having pairs of coin passages 20 extending from the top to the bottom thereof, the passages 20 of each pair being separated by a magnet 21 which is secured to the guide plate 19 in

any manner desired and has its lower end rounded. The upper ends of the passages 20 are in communication with semi-circular coin slots 22 formed in the front plate 8, while the lower end of each passage 20 is located directly above one of the slots 16. Thus a coin deposited in either opening 22 will gravitate along the passage 20 thereunder to the slot 16 alining with the passage. The lower ends of the passages 20 of each pair are separated by deflecting webs or partitions 23 which are extended toward the lower end of magnet 21 and form between them a slug receiving space 24 registering with one of the slots 17 and communicating with the coin passages 20 between the deflecting webs 23 and the magnet 21. Thus should a slug be inserted into the coin slot or opening 22 it will gravitate for a distance along the coin passage 20 but will adhere to the magnet 21 and thus be deflected by said magnet to a position directly above the space 24 whereupon it will be released and will fall into said space 24 and slot 17.

That portion of the plate 19 directly over each of the slots 16 is cut away or arched, as shown at 25. A cover 26 is secured upon the rear or inner portion of the guide plate 19 so as to close the passages 20, this cover being likewise arched or cut away at its lower edge, as shown at 27 so as to register with the arched or cut away portion 25.

An arm 30 is extended rearwardly from the middle portion of the guide plate 19 and through the cover 26 and has a depending finger 31 in which is slidably mounted a plunger 32 the front end of which is slidably mounted in the front plate 8. This plunger 32 is secured to the bottom of the slide 14 so that when the plunger is pressed inwardly the slide will be moved therewith inwardly away from the front plate 8. Coiled springs 33 or the like are secured to the front plate 8 and to the plunger 32 and serve to hold the plunger normally projected and the slide 14 normally pressed against the plate 8, as shown in Fig. 2.

Arms 28 are extended inwardly from the sides of the guide plate 19 and have inturned ears 29 at their rear ends. These arms 28 are adapted to receive between them a wedging block 34 formed of wood or any other suitable material and which bears downwardly on the cover 26, the same wedging between said cover and the ears 29 so as thus to be supported. The rear or inner face of the wedging block 34 is substantially vertical and has secured to it a series of spaced channel members 35 constituting magazines which are open at their upper and lower ends and at the back or inner sides thereof. The walls of these magazines are held close to the slide 14 and have inwardly extending package supporting flanges 37 and longitudinal retaining flanges 130

along the rear edges of the side walls, as shown at 38. These flanges 38 are cut away at their lower ends, as shown at 39, to permit the ejection of a package from between 5 the supporting flanges 37 and the lower ends of the retaining flanges 38. The front wall of each magazine has its lower end cut away or arched, as shown at 40', thus to permit the passage under said wall of the upper portion of a deposited coin, as will be explained hereinafter. These front walls of the magazines are supported directly back of the vertical plane in which the slots 16 and 17 are located, as will be seen by referring particularly to Figs. 2, 4 and 5.

Ears 40 extend upwardly from the arms 13 and support a rod 41 which extends transversely across the back faces of the magazines near the lower ends thereof. 10 This rod is for the purpose hereinafter pointed out.

Fixedly connected to the arms 13 below the slide 14 is a coin shelf 42 extending throughout the width of the front plate 8 and spaced, at its front edge, from said plate. The front edge of this shelf 42 is disposed in substantially vertical alinement with the series of slots 16 and 17, those portions of the shelf 42 under the slug receiving slots 17 being cut away or recessed as shown at 43 in Figs. 4 and 5, thus to permit a slug to fall freely through its slot 17 and past the shelf 42. Upstanding from the front edge of the shelf 42 below the end 25 portions of each slot 16 are coin supporting fingers 44. As shown particularly in Fig. 3 these fingers are arranged in pairs and converge upwardly, the distance between the upper ends of the fingers of each pair being 30 slightly less than the diameter of a deposited coin so that, when a coin is discharged into a slot 16 and the space between the depending ears 18, it will be supported by the upper ends of the fingers 44 as long as the slide 40 45 14 remains in its normal position. That portion of the front edge of shelf 42 between the fingers 44 of each pair is beveled or rounded, as shown at 45, thus to deflect past the edge of the shelf 42 any object which 50 may be smaller than the coin intended for use. Formed in the upper face of the shelf 42 directly back of the space between each pair of fingers 44 is a series of notches 46 having substantially vertical front walls 55 and inclined rear walls, as shown in Figs. 2 and 6, these notches being designed to receive the lower edge of a deposited coin and thus constitute a rack with which the coin co-operates as will be pointed out herein- 60 after.

Extending inwardly from the lower edge portion of the front plate 8 is a base or support 47 on which is mounted a coin receptacle 48 extending throughout the width of the front plate 8 and located below but

spaced from the shelf 42. The front wall of the coin receptacle 48 is spaced from the front plate 8 to form a delivery passage 49 opening downwardly onto the tray 3. Extending upwardly from the front wall of the receptacle 48 are deflecting shields 50 and 51. The deflecting shields 50 overhang the receptacle 47 and up close to and under the shelf 42 and under the beveled portions of the shelf 42. Thus any article directed over the beveled edges 45 of the shelf 42 will be deflected into the passage 49 and delivered to tray 3. The deflecting portions 51 extend outwardly away from the receptacle 48 and against the front plate 8 and are located in front of the recesses 43 in shelf 42 so that, when a slug is directed into the machine it will pass directly through the recess 43 and into the coin receptacle 48.

Pivottally mounted on the rod 41 is a series of leaves 52, one leaf being provided for each magazine 35. Each leaf is provided at one side with a depending arm 53 located directly back of the space between two of the magazines and extending laterally from the lower end of each arm 53 is a coin shutter 54'. This coin shutter is designed to close the space between the shelf 42 and the rear wall of the coin receptacle 48 and it is held pressed against the shelf 42 and the coin receptacle by a weighted finger 54 extending downwardly from one side portion of the leaf 52 and in the path of the lowermost article contained within the magazine with which the leaf is combined. 90 In other words, this weighted finger 54 is so positioned that when the lowermost article in the magazine is ejected rearwardly from the magazine, it will press against the finger 54 and swing it upwardly, thus causing the coin shutter 54' to swing inwardly and upwardly away from the shelf 42 and the receptacle 48, as shown in Fig. 6. Importance is attached to the fact that the arm 53 is not located directly back of the magazine but, instead, is located beyond one side of the magazine where it will not hinder the falling of a package when delivered from the magazine. 105

It is to be understood of course that each magazine 35 is to contain a stack of packages X, there being an arched weight 55 resting on each stack. The lowermost package of each stack bears upon the supporting flanges 37. A coin of proper denomination can be 110 inserted into any one of the openings 22 and will gravitate along the passage 20 thereunder and into the slot 16 with which the passage communicates. The coin will enter the space between the ears 18 and will rest upon and between the fingers 44, the upper portion of the coin projecting above the slide 14. The operator now pushes the plunger 32 inwardly with the result that the coin is pushed by the front ear 18 off of 115 120 125 130

the fingers 44 and gravitates onto the shelf 42. During the inward movement of the plunger the slide 14 is likewise shifted inwardly and the coin is thus dragged over 5 the shelf 42 and is brought successively into the notches 46 so as thus to act as a pawl and prevent the return of the plunger to its initial position. As the coin is thrust rearwardly in the manner pointed out, the upwardly projecting portion of the coin will pass through the recess 27 and the corresponding recess in the front wall of the magazine 35 and will thrust against the lowermost package in the magazine, thus 10 sliding said package from under the stack and to the position shown in Fig. 6. During this ejection of the package from the stack, it will come against the weighted finger 54 and swing said finger inwardly and upwardly with the result that the shutter 54' will be swung inwardly away from the coin 15 receptacle 48. As the inward movement of the plunger and slide continues the coin, which has been indicated generally at Y, will 20 slip over the rear edge of the shelf 42 and will drop into the receptacle 48, this action taking place just as the package is pushed off of the supporting flanges 37 and onto the rearwardly extended slide 14. It might be 25 stated that the slide is formed with recesses 56 in the rear edge thereof so that the rearward movement of the slide will not be interfered with by the depending arms 53. The parts remain in these positions until the 30 plunger 32 is released, whereupon the springs 33 will restore it automatically to its initial position, thereby withdrawing the slide 14 from under the package thereon so that said package will gravitate off of the slide. Be- 35 fore the package drops from the slide the finger 54 will be relieved of the sustaining action of the package and will automatically restore the shutter 54' to its closing position as shown in Fig. 5 so that when the package 40 falls it will not drop into the coin receptacle 48 but will fall into the space between said receptacle 48 and the back of the casing 1 and will thus gravitate into the tray formed by the bottom of the casing, where 45 it can be easily reached and removed. As the arm 53 is located at one side of the shutter 54', it will be seen that the package can drop straight down behind the coin 50 receptacle 48 without coming into contact with said arm 53. Consequently there is no danger of the package becoming hung and clogging the machine, as would be the case should the arm be extended upwardly from the middle portion of the shutter 54'. Fur- 55 thermore by utilizing the weighted finger 54, the shutter and its parts can be more cheaply constructed as it is unnecessary to utilize a spring to hold the shutter in closed position. 60

65 Should the magazine be empty, a coin

when deposited, would be directed onto the fingers 44 as before described and would be thrust rearwardly with the plunger 32 and the slide 14. However, as there would be no package for the coin to engage and thrust 70 rearwardly, the shutter 54' would not be swung inwardly during this inward movement of the coin and, consequently, when the coin is discharged over the rear edge of the shelf 42, it will gravitate onto the shutter 75 54' while said shutter is in the position shown in Fig. 5 with the result that instead of falling into the receptacle 48, the coin will fall into the space back of said receptacle and be returned to the customer. 80 Should a person tampering with the machine push the plunger 32 inwardly and then deposit a coin, said coin would fall upon that portion of the slide 14 between the front edge thereof and the slots 16 and should the 85 user continue to push inwardly on the plunger after the coin has been deposited under these conditions, the said coin would slip over the front edge of the slide 14 as said slide is thrust inwardly and thus drop onto 90 one of the deflecting wings 50 and be discharged through passage 49 into the space 3 under the receptacle 48. If instead of continuing to push the plunger 32 inwardly, the operator should release the plunger, the 95 slide would return to its normal position and thus bring the slot 16 under the coin so that the coin would enter the slot and become seated on the fingers 44 whereupon it will not be returned to the customer unless 100 the magazine is empty but, instead, a package will be delivered to the customer.

Should a slug be inserted into the machine it will not fall straight down through the passage 20 but will be deflected laterally by 105 the magnet 21 and will fall into the space 24 and thence through slot 17 and recess 43 into the coin box 48 so that the slug will not be returned to the user.

The machine hereinbefore described would 110 not, of course, be suitable for use between windows of street cars or the like, or at other places where only narrow spaces are provided. For such purposes, a machine such as has been illustrated in Figs. 7 to 13 in- 115 clusive is preferably employed. This machine contains but a single magazine consisting of a longitudinally channelled member 57, said member being open at the top and back and being provided, along the rear 120 edges of its side walls, with retaining flanges 58 terminating some distance above the bottom of the magazine. Wings 59 extend rearwardly from the side walls at the lower end of the magazine and below these wings the 125 said side walls merge into the side walls of a coin receptacle 60 the bottom of which is adapted to be closed by a slide 61 suitably supported. The side walls of the coin receptacle are likewise integral with the side 130

walls of a tray 62 located under the receptacle and the rear portion of the bottom of which is upturned, as shown at 63, to constitute a deflector, while the front edge of 5 said bottom of the tray is upturned as at 64 to constitute a retaining flange. The wall of the tray 62 is extended rearwardly beyond the coin receptacle 60 as shown at 65. A guide plate 66 is secured to the front 10 face of the magazine 57 and extends a short distance below the bottom of the magazine, the lower edge of this plate 66 being formed with a segmental recess 67 at the sides of which are arranged deflectors 68 which 15 converge downwardly toward the recess 67. The front wall 69 of the coin receptacle 60 is supported with its outer or front face flush with the front faces of the deflectors 68 and has a segmental recess 70 in its upper edge 20 below but in front of the recess 67 so that an object gravitating along the front face of the plate 66 and between the deflectors 68, will pass through recess 67 and back of recess 70 into the coin receptacle 60, as will be 25 apparent by referring to Fig. 8.

A segmental coin receiving opening 71 is formed in the guide plate 66 at the upper end of a coin passage 72 formed within said plate, a portion of one side wall of this 30 passage being formed by a magnet 73 secured in any suitable manner to the plate 66. Below this magnet the side wall of passage 72 opens into a recess 74 formed in the front of the plate 66, the bottom of the recess being 35 beveled as at 75 so that an article deflected laterally from passage 72 into recess 74 will gravitate onto the beveled bottom 75 of the recess and thus pass out of the recess and into the space between the deflectors 68.

40 Extending rearwardly from the guide plate 66 and adjacent opposite sides of the lower end of passage 72 are channeled guide arms 76 connected by an arcuate shelf 77 the front edge of which is spaced from the plate 66, as shown particularly in Fig. 8. This 45 shelf 77 has notches 78 corresponding with the notches 46 hereinbefore referred to. Mounted within the channeled guide arms 76 is a slide 79 from which extends a plunger 50 80. Lugs 81 extend downwardly from the rear portion of the slide at the sides thereof and are connected by springs 82 to the guide plate 66. These ears or lugs 81 extend into recesses 83 in the bottom portions of the 55 rear ends of the guides 76 and the springs serve to hold the ears normally seated in these recesses 83 and with the front end of the slide 79 substantially flush with the front face of the guide plate 66. The slide has a 60 slot 84 which normally registers with the lower end of the passage 72 and depending from the slide at the front and back of the slot, are ears 85 and 86 forming a coin receiving space therebetween. The guides 76 65 are provided, upon the inner sides of their

forward portions, with coin engaging ribs 87, the distance between the ribs being slightly less than the diameter of the coin used in connection with the machine so that when a coin is deposited in the slot 84 it 70 will be supported by these ribs 87 while suspended above the space between the shelf 77 and the front wall of the magazine. The front wall of the magazine is formed with a recess directly above the slide 79, as shown 75 at 88 so as to permit the coin which is seated in slot 84 to move rearwardly with the slide 79 and out of the lower portion of passage 72.

Pivottally mounted between the side walls 80 of the coin receptacle 60 and at the upper edge of the rear wall of said receptacle, is a coin shutter 89, the upper edge of this shutter normally extending under the rear edge of the shelf 77. A coiled spring 90 85 connects the shutter to the front wall of the magazine so as to hold said shutter normally pressed against the side walls of the magazine, there being laterally extending fingers 91 upon the sides of the shutter which are 90 adapted to bear against the wall of the magazine as shown particularly in Fig. 10.

Extending back of the shutter 89 is an arm 92 projecting from one end of a rod 93 which is mounted for rotation in the wings 95 59. These wings are provided with vertical series of apertures 94 and any one of the apertures of each series is adapted to receive the rod. Thus it will be seen that the rod can be adjusted upwardly or downwardly 100 relative to the coin receptacle and to the slide 79. This adjustment may be effected without withdrawing the arm 92 from back of the coin shutter 89.

Rod 93 is provided, at an intermediate 105 point, with a loop or extension 95 which is normally inclined downwardly and rearwardly so as to be engaged and lifted by a package while being ejected rearwardly from the magazine.

Guides 96 are formed on or secured to the flanges 58 near the rear ends thereof and are slidably engaged by gage strips 97 having finger pieces 98 at their upper ends, whereby said strips can be adjusted upwardly or downwardly, thus to vary the size 115 of the opening through which the packages are to be ejected from the magazine.

The front wall of the magazine is provided, at its upper end, with parallel slits 120 99 forming spring tongues or tumblers 100 the upper ends of which are bent outwardly to form lugs 101.

The entire structure hereinbefore described and which includes the magazine, 125 the coin receptacle, and the parts coöperating therewith, is adapted to be inserted longitudinally within an angular tube 102 closed at its upper end and open at its lower end, the magazine and coin receptacle fitting 130

snugly in this tube and there being an opening 103 through which the plunger 80 is adapted to snap after the mechanism has been inserted in the casing 102 and within 5 which the plunger is adapted to work. An additional segmental opening 104 is formed in the front of the casing 102 and is adapted to register with the opening 71 in the magazine wall. The front face of the casing 102 10 is cut away at its lower end, as shown at 105, thus to provide an outlet opening through which access may be had to the contents of the tray 62. A shoulder 106 is formed upon the inner side of the front 15 wall of casing 102 at the top thereof and, when the magazine and the parts connected thereto is inserted into the casing 102, the outturned ends 101 of the tumblers 100 are adapted to snap into engagement with the 20 shoulder 106 and thus lock the casing in position. The only way in which the casing can then be removed from the magazine and the mechanism adjacent thereto, is to insert a key capable of forcing the tumblers 100 25 out of engagement with the shoulder 106. After the tumblers have thus been disengaged, the plunger 80 is pushed inwardly through the opening 103 whereupon the magazine and the parts connected thereto 30 can be pulled out of the casing 102.

The operation of this modified form of machine is similar to that of the large machine hereinbefore described. The stack of packages is placed in the magazine under a 35 weight 107 after which the magazine, coin receptacle, and parts connected thereto, are inserted into the casing, and will lock as before pointed out. When a coin of proper denomination is inserted in the opening 104 40 it will gravitate along passage 72 and drop into the slot 84 in which it will be supported by the ribs 87 extending to opposite sides of the ears 85 and 86. The coin will project upwardly above the slide 79 in back of 45 the lowermost package of the stack. By now pressing inwardly on the plunger 80 the upper portion of the coin will thrust the lowermost package rearwardly and against the projection 95, thus causing the rod 93 to 50 rotate and the arm 92 to press against the shutter 89 and swing said shutter outwardly beyond the rear edge of the shelf 77. The coin will gravitate off the ribs 87 and pass over the notches 78 during this operation 55 and will ultimately drop over the rear edge of the shelf 77 and fall into the receptacle 60. Immediately subsequent to this operation the plunger 80 can be released and will be returned to its initial position by the 60 springs 82 whereupon the package which was supported by the slide 79 will drop. Before the said package reaches the shutter 89, said shutter will have been returned to its normal position by spring 90, with the 65 result that the package will be caused to

fall between the rear wall of casing 102 and of the coin receptacle 60 and will fall onto the tray 62. Should the magazine be empty the coin will pass through the machine as hereinbefore described but, instead of falling into the coin receptacle 60, will drop 70 into the tray 62 for the reason that there is nothing in the machine to open the shutter 89. Should a slug be inserted into the passage 72 it will be deflected therefrom by the 75 magnet 73 and passed over the beveled bottom 75 of recess 74 and gravitate between the deflectors 68 and then downwardly into coin receptacle 60 as hereinbefore pointed out. 80

By providing the adjustable strips 97 and the adjustable rod 93, the machine can be quickly adjusted to use packages of different thicknesses.

By providing semi-circular coin receiving 85 slots 22 and 104, it is impossible to insert into the machine any object unless it be a circular one equal to or less than the thickness of the proper coin to be used, and less than or equal to the diameter of the coin to 90 be used. The use of angular slugs and the like is prevented.

What is claimed is:—

1. In a vending machine, a shelf, a slide thereabove having spaced coin receiving slots 95 and an intermediate slug receiving slot, a front plate having spaced coin receiving openings, a guide plate having passages leading from said coin receiving openings to the coin slots, a magnet separating said passages and overhanging but spaced from the slug receiving slot, deflecting means disposed between the slug receiving slot and the coin receiving slots.

2. The combination with a front plate, a 105 magazine, and a coin receptacle spaced from the front plate and below the magazine, of a shelf interposed between the magazine and coin receptacle and spaced from the front plate, a slide having a coin receiving slot 110 interposed between the shelf and the magazine, coin supporting means upstanding from the shelf and normally below the end portions of the coin receiving slot for holding a coin within the slot and out of contact with the shelf, there being sufficient clearance between said coin supporting means below the upper end thereof to permit the passage of a coin therebetween and through the space between the shelf and front plate, and deflecting means overhanging the coin receptacle for directing a coin from said space between the front plate and the shelf and downwardly past the coin receptacle. 115

3. In a vending machine, the combination with a magazine, a coin receptacle thereunder, and a shelf interposed between the magazine and the receptacle, of a coin receiving slide between the magazine and shelf, a 130

pivot member above the lower end of the magazine, an arm suspended therefrom, a coin shutter supported by the arm and normally bearing against the edge of the shelf 5 and the top of the coin receptacle to prevent the dropping of a coin into the receptacle, a weighted arm movable with the first mentioned arm and extending into the path of a package being ejected from the 10 magazine, said first mentioned arm being disposed at one side of the path of said package.

Copies of this patent may be obtained for five cents each, by addressing the "Commissioner of Patents, Washington, D. C."

In testimony that we claim the foregoing as our own, we have hereto affixed our signatures in the presence of two witnesses.
